[57] ABSTRACT

Cephalosporin C is produced in remarkably increased yields by fermentation process using a cephalosporin C-producing polyploid mold belonging to the genus Cephalosporium.

3 Claims, No Drawings

PRODUCTION OF CEPHALOSPORIN C

This invention relates to the production of cephalosporin-C (hereinafter abbreviated as "CPC") by fermentation processes, and is particularly concerned with processes for the production of CPC using a CPC-producing polyploid mold belonging to the genus *Cephalosporium*.

Methods by which increased yields of CPC produced by fermentation processes may be obtained have been investigated, but few methods are known in which selective breeding of microbial strains is involved. All that is known at the present time are the methods enlisting the help of a strain whose metabolism and biosynthesis of organosulfur compounds have been blocked (Japanese patent application laid open No.1828/1971) and those in which the CPC-producing ability of microorganisms has been somehow enhanced (U.S. Pat. No. 3,082,155 and Japanese patent application laid open No.26986/1973). Moreover, in regard of the abilities of microorganisms to produce CPC, the fermentation yields are 760 $\mu\text{g}/\text{ml}$ at best in the case of the Japanese patent application laid open No.1828/1971, about 500 $\mu\text{g}/\text{ml}$ in the case of U.S. Pat. No. 3,082,155 and, even in the most satisfactory of all the cases heretofore reported, Japanese patent application laid open No. 26986/1973, the attainable potency is not more than 5,000 $\mu\text{g}/\text{ml}$.

The present inventors have attempted to find a way to produce CPC in an increased yield through intensive research directed to a genetic improvement of microorganisms, and have ultimately found that molds possessing excellent CPC-producing abilities can be obtained at a higher frequency from among polyploid molds induced by polyploidizing treatment of CPC-producing microorganisms belonging to the genus *Cephalosporium*, than from among other mutants induced by other conventional mutation treatment, and that some of the polyploid molds are able to accumulate CPC extracellularly in unprecedentedly high concentrations.

Though attempts have heretofore been made to improve the fermentation yields of contemplated products by microbial polyploid strains, none of the reported cases have been industrially successful, either because of the failure to achieve satisfactory results or because of the difficulty with which these strains lend themselves to genetic fixation of characters. Of course, there is not a single reported case of attempt in connection with CPC fermentation.

This invention is directed to a method for the production of CPC comprising cultivating the polyploid microorganisms induced from parent microorganisms of the genus *Cephalosporium* having CPC producing ability in a culture medium to let the microorganism accumulate CPC extracellularly.

As the parent strains of microorganisms that are employed in this invention, use can be made of any suitable CPC producer of the genus *Cephalosporium*, for example, *Cephalosporium acremonium* or *Cephalosporium polyaleurum*.

As typical strains of the species, there may be mentioned, among others, *Cephalosporium polyaleurum* Y-505 (FERM-P No.1160), *Cephalosporium acremonium* ATCC-11550, *Cephalosporium acremonium* ATCC-14553, etc., and various mutants induced from these strains.

The FERM-P and ATCC numbers indicate the accession number of the organisms at the Research Institute of Fermentation of the Agency of Industrial Science and Technology, Chiba, Japan and at American Type Culture Collection, Rockville, Md., U.S.A., respectively.

The following two procedures may be cited as principal procedures for inducing desired polyploid microorganisms from parent microorganisms.

One of them is the procedure comprising polyploidizing microbial cells with a chemical agent. As examples of said chemical agent, there may be mentioned camphor, acenaphthene, colchicine, etc. While the conditions of treatment vary with the particular mold, type of chemical agent and other factors, the following procedure generally can be followed with success. Thus, in the case of camphor or acenaphthene, for instance, microbial cells are exposed to a vapor of the chemical for a few to tens of hours, after which they are removed from the ambient vapor and further cultivated. In another scheme, the cells are cultivated from the beginning on an agar plate containing the chemical. The grown cells taken from the resulting colonies are examined, e.g., under a microscope. The colonies made up of giant cells are selectively taken.

By either of the above-described procedures there can be obtained the desired polyploid mold. For example, a polyploid mold can be obtained by the method described in Journal of General and Applied Microbiology 2, 345(1956). These procedures cannot only be followed in repetition but can be followed in combination with other methods of breeding and selecting some specific microbial strains and, in such instances, improved results are sometimes obtained.

The polyploid strains thus obtained can be easily isolated, if desired, by a conventional pure-isolation method, for example by micromanipulation.

To illustrate, *Cephalosporium acremonium* ATCC-14553 as a parent strain was treated with camphor and the CPC-producing abilities of the resulting polyploid strains were investigated. The investigation resulted in the finding of the number of strains which can accumulate CPC in the medium in the increased yields, for example, more than 7,000 $\mu\text{g}/\text{ml}$, with *Cephalosporium acremonium* 2M-16 (FERM-P No.2283, ATCC-20425, IFO-9999), in particular, giving an unprecedentedly high yield of CPC. The taxonomic characters of this strain were found to be essentially identical with those of *Cephalosporium* sp. ATCC-14553 (Japanese patent publication No.4437/1965) except the differences noted in Table. 1.

The IFO number indicates the accession numbers of the organisms at the Institute for Fermentation, Osaka, Japan.

Table 1

Strain	Size of arthrospore		Number of nuclei per arthrospore (A)	DNA content per arthrospore (B) (μg)	Amount of DNA per nucleus (B/A) (μg)
	Major diameter (μ)	Minor diameter (μ)			
<i>Cephalosporium</i>					

Cephalosporium

Table 1-continued

Strain	Size of arthospore		Number of nuclei per arthospore (A)	DNA content per arthospore (B) (μg)	Amount of DNA per nucleus (B/A) (μg)
	Major diameter (μ)	Minor diameter (μ)			
acremonium ATCC-14553	7.2	3.6	1.0	0.30×10^{-7}	0.30×10^{-7}
Cephalosporium acremonium 2M-16	11.2	4.7	3.2	1.98×10^{-7}	0.62×10^{-7}

(Note: All the values given in the above table are the results on analysis of the arthospores obtained after 2 weeks' incubation at 28°C on an agar medium composed of 0.25 % yeast extract, 0.5 % malt extract, 0.1 % casein hydrolyzate (Casamino acid), 2.0 % sucrose, 1.5 % glycerin and 2.0 % agar. The dimensions of the arthospore and the number of nuclei are the mean of results for approximately 100 arthospores. The mean dimensions of conidia are $3.5 \mu \times 7.1 \mu$ in the case of ATCC-14553 and $4.3 \mu \times 8.6 \mu$ in the case of 2M-16).

20

many superior CPC-producing strains which can accumulate CPC extracellularly in the concentration of, for example, more than 7,000 μg/ml, with *Cephalosporium acremonium* LA-101 (FERM-P No.2284, ATCC-20426, IFO-30001), in particular, giving an unprecedentedly high yield of CPC.

The taxonomic characters of this strain were found to be essentially identical with the characters of *Cephalosporium* sp. ATCC-14553 except the differences noted in Table 2.

Table 2

Strain	Size of conidium		Number of nuclei per conidium (A)	DNA content per conidium (B) (μg)	DNA content per nucleus (B/A) (μg)
	Major diameter (μ)	Minor diameter (μ)			
<i>Cephalosporium acremonium</i> ATCC-14553	10.5	2.5	1	0.691×10^{-7}	0.691×10^{-7}
<i>Cephalosporium acremonium</i> LM-5	7.5	2.3	1	0.670×10^{-7}	0.670×10^{-7}
<i>Cephalosporium acremonium</i> AP-78	7.3	2.7	1	0.710×10^{-7}	0.710×10^{-7}
<i>Cephalosporium acremonium</i> LA-101	7.9	3.3	1	1.380×10^{-7}	1.380×10^{-7}

The second genetic method typically comprises the procedure described in *Journal of General and Applied Microbiology* 2, 401(1956). Thus, the two strains to be crossed are differently marked beforehand, e.g., with different amino acid or vitamin requirements. They are crossed and grown on a minimal medium (e.g., a medium made up of 3.0 % sucrose, 0.3 % NH_4NO_3 , 0.1 % K_2HPO_4 , 0.05 % $\text{MgSO}_4 \cdot 7\text{H}_2\text{O}$, a trace of $\text{FeSO}_4 \cdot 7\text{H}_2\text{O}$ and 1.5 % agar) in the conventional manner. The conidia of grown colonies are collected and plated onto a minimal medium such as the one indicated above and the colonies formed are investigated. Most of the growth consists of polyploid strains.

If necessary, these methods cannot only be practiced in repetition but can also be carried out in combination with other selective breeding procedures, and improved results can be obtained thereby. The resultant polyploid strain can be easily isolated, if desired, by a known pure-isolation method such as micromanipulation.

Using *Cephalosporium acremonium* LM-5, which is a methionine-leucine-requiring mutant, and *Cephalosporium acremonium* AP-78, an arginine-phenylalanine-requiring mutant, both induced from *Cephalosporium acremonium* ATCC-14553 as the parent strain, a number of polyploid strains were obtained by the procedures hereinbefore described.

An investigation of the abilities of these polyploid strains to accumulate CPC resulted in the finding of

(Note: Each of the values given above is the result of analysis of the conidia harvested from a slant culture grown by the procedure set forth in the footnote to Table 1. The dimensions of conidia and the number of nuclei are the mean values for about 100 spores.)

To cultivate these polyploid strains, the known methods for culture of other CPC producers of the genus *Cephalosporium* or those of the genus *Emericellopsis* can be employed to advantage.

As the carbon sources that can be employed, there may be mentioned, for example, glucose, sucrose, starch, soluble starch, waste molasses, n-paraffins, acetic acid, methanol, ethanol, etc. As the organic nitrogen sources, mention may be made of urea, meat extract, peptone, soybean meal, cotton seed cake, peanut cake, dried yeast, corn steep liquor, etc., while ammonium chloride, ammonium sulfate, ammonium nitrate, ammonium phosphate, potassium nitrate, etc. may be mentioned as the useful inorganic sources of nitrogen. If necessary, there may be added such metal salts as the SO_4 , Cl , NO_3 , CO_3 , PO_4 and other salts of Na , K , Ca , Mg , Mn , Zn , Fe , Cu , etc.

Furthermore, there may also be added, as required, amino acids (e.g., methionine, cysteine, serine), thiosulfates, fatty acid esters, oils, e.g., lard oil, olive oil, etc., and other agents which assist in the production of CPC, whereby the potency of CPC can be further increased.

As to the conditions of cultivation, aerated submerged culture is generally advantageous. The temperature is desirably within the range of 18° to 35°C. Satisfactory results are obtained when the pH is maintained within the range of about 2 to 10 and, preferably, between 4 and 9. A cultivation time of 3 to 15 days is sufficient. Most of the CPC elaborated occurs in filtered broth and, therefore, to recover the antibiotic, it is advantageous to remove the cells from the broth by centrifugation or filtration and, then, purify CPC from the supernatant or filtrate. To isolate the CPC, the procedures generally used for the fractional recovery of CPC can be followed with success. For example, the desired result can be obtained with advantage by utilizing an ion exchange resin, activated carbon, nonionic copolymer resin, gel filtration medium, etc. in a suitable combination. The following examples are merely illustrative of this invention and should by no means be construed as limiting the scope of the invention.

EXAMPLE 1

A Sakaguchi flask of 2-liter capacity is filled with 500 ml of an inoculum medium made up of 3.0 % of sucrose, 1.5 % of meat extract, 0.5 % of corn steep liquor and 0.15 % of CaCO_3 and, after sterilization, inoculated with *Cephalosporium acremonium* 2M-16. The flask is incubated on a reciprocating shaker at 28°C for 3 days. Meanwhile, a 50-liter fermentation tank of stainless steel is charged with 30 liters of a medium made up of 6 % of sucrose, 5 % of glucose, 3 % of peanut cake, 3 % of soybean meal, 1.0 % of DL-methionine and 0.15 % of CaCO_3 , and the medium is sterilized and cooled in the routine manner. The medium is then aseptically inoculated with the above seed culture and incubated at 28°C under sparging and agitation (30 l. per min. aeration, 250 r.p.m.)

After 190 hours of cultivation, the culture broth is withdrawn and filtered free of solids. The resultant

filtrate (25 l.) is assayed for CPC. The potency found is 8,200 $\mu\text{g}/\text{ml}$. The fractional isolation of CPC is carried out in the following manner. The filtrate (25 l.) is run down a column of activated carbon (20 l.), whereby the CPC is adsorbed on the carbon. The carbon is first washed well with water and, then, eluted with 5 % aqueous butanol containing 0.01 N NaOH, whereupon 31 l. of CPC fractions are obtained. These fractions are pooled, concentrated and neutralized to pH 7.0 with NaOH. Finally, ethanol is added to the concentrate to a concentration of 50 % (V/V).

The procedure gives 143 g. crude crystals of CPC sodium dihydrate.

The potency of CPC is measured by an enzymatic assay method using the cephalosporinase of *Aerobacter cloaceae* [Biochemical Journal, 116, 385 (1970)].

EXAMPLE 2

20 The same cultivation as in Example 1 is carried out, except that the strain used is *Cephalosporium acremonium* LA-101. The potency of CPC in the filtered broth is 7,900 $\mu\text{g}/\text{ml}$.

What is claimed is:

25 1. A process for producing cephalosporin C which comprises cultivating *Cephalosporium acremonium* ATCC 20425 or *Cephalosporium acremonium* ATCC 20426 in a culture medium containing an assimilable carbon source and a digestible nitrogen source, to accumulate cephalosporin C in the culture medium, and recovering the accumulated cephalosporin C from the culture medium.

30 2. A process according to claim 1, wherein the micro-organism is *Cephalosporium acremonium* ATCC-20425

35 3. A process according to claim 1, wherein the micro-organism is *Cephalosporium acremonium* ATCC-20426.
